UNDERGARMENT SUPPORT

Ethel A. Wangenheim, San Francisco, Calif.

Application December 15, 1936, Serial No. 115,924

1 Claim. (Cl. 2—42)

My invention relates to improvements in undergarment supports, and it consists of the combinations, constructions and arrangements hereinafter described and claimed.

5 An object of my invention is to provide an undergarment support that is designed to be attached to an undergarment such as a brassière or corselette and adjustably attached to an outer garment. The support is so designed as to be 10 disposed along the front portion of the wearer's body rather than the back portion. This will permit backless evening gowns to be worn and will obviate the unsightly appearance of straps extending along the back of the wearer. The 15 undergarment support is adjustably secured to the outer garment whether the outer garment is provided with portions that go over the shoulder of the wearer or even without such portions.

The support primarily consists of a strap 20 preferably provided with an elastic portion, the opposite end of the strap carrying a snap or other suitable fastening member that is designed to be removably secured in complementary snaps disposed along the body of the strap. Two straps 25 are secured to the front of the undergarment, and then the free ends of the straps are passed through lingerie straps provided in the outer garment. The free ends of the undergarment supporting straps then are looped back upon 30 themselves, and the complementary snaps are secured together to provide the proper length of effective strap portion between the lingerie straps and the undergarment. I have found that the undergarment will be properly supported by the 35 adjustable straps, and this leaves the back of the wearer entirely free of any straps.

Other objects and advantages will appear in the following specification, and the novel features of the device will be particularly pointed 40 out in the appended claim.

My invention is illustrated in the accompanying drawing forming a part of this application, in which

Figure 1 shows the undergarment straps applied in position;

Figure 2 shows a rear view of the undergarment illustrating the freedom of any straps for this portion of the garment;

Figure 3 is a front elevation of two of the devices shown operatively applied to an undergarment; and

Figure 4 is a section along the line 4—4 of Figure 1.

In carrying out my invention I provide a pair 55 of straps indicated generally at 1. These straps

may be made from any material desired, and can be of a length suitable to the wearer. Each strap 1 has a non-elastic portion 2 and an elastic portion 3. The elastic portion 3 preferably is permanently secured to an undergarment such as 5 a brassière 4. The non-elastic portion 2 of the strap has a fastening member such as a snap 5 disposed at its outer end. The body of the portion 2 carries a plurality of complementary snaps 6. The effective length of the strap can be altered by merely attaching the snap 5 to any desired complementary snap 6.

In Figures 1 and 2 I show the undergarment 4 worn by a person. Figures 1 and 4 show an outer garment 7 provided with lingerie straps 8 attached to shoulder portions 9 of the garment. The supporting straps 1 are threaded through the lingerie straps 8, and then are looped back upon themselves as shown in Figure 4. The snap 5 is connected to the desired complementary snap 6 so that the strap 1 will act as a support between the lingerie strap 8 and the undergarment 4. In this way the undergarment will be supported properly by straps that are only disposed in front of the wearer. This 15 obviates the necessity of providing straps that go over the shoulders and are connected to the front and back of the undergarment.

In Figure 2 the undergarment 4 is shown as a brassière and the ends 10 of the brassière are 20 connected together by a hook and eye 11, or other suitable fastening means. The back of the brassière extends low enough so as not to show when the gown 7 has a backless portion 12. It also will be seen that there are no straps 25 to show from the back of the person.

I do not wish to be confined to supporting the straps 1 at the shoulders of the outer garment because it is obvious that the lingerie straps 8 may be attached to any portion of the outer 30 garment as long as they are positioned above the top of the undergarment. The straps 1 may be adjusted as to length to accommodate them to the wearer and the type of the undergarment worn. The elastic portions 3 of the straps 1 permit 35 sufficient yield during the wearing of the device.

I claim:

The combination with a backless outer garment provided with shoulder portions and lingerie straps secured to the underside of the shoulder portions, and an undergarment, of straps having only one of their ends secured to only the front of the undergarment, the free ends of the last-named straps being disposed 50 55

beneath the shoulder portions so as to be covered thereby, and passed through the lingerie straps, said undergarment supporting straps being bent back upon themselves, and cooperating means carried by the ends of the undergarment straps and at spaced distances from the ends for adjusting the effective lengths of the straps for

causing them to connect the front of the undergarment to the lingerie straps, whereby the undergarment is supported without exposing any straps on the backless portion of the outergarment.

ETHEL A. WANGENHEIM.
